COLD WALL REFRIGERATOR WITH OPEN MESH PRODUCE CONTAINERS

Carlyle E. Hartman, San Jose, Calif.

Application May 21, 1948, Serial No. 28,301

9 Claims (Cl. 62—89.5)

1

The present invention relates to improvements in refrigerating apparatus and has particular reference to open-top display refrigerators employing a so-called cold wall as a cooling medium.

One of the principal objects of the invention is to provide refrigerating apparatus of the character described in which a certain amount of air movement or circulation is set up to pass through the produce accommodated in the apparatus from the sides and from the bottom to effect a thorough cooling of the produce throughout the mass thereof in a short period of time and with a substantial degree of uniformity.

A further object of the invention is to arrange the air circulating means in such a manner that the moving air will absorb or entrain moisture from the space outside the apparatus and convey the same to the produce for substantially uniform distribution whereby the produce is kept fresh and salable for a considerable time period.

A still further object of the invention is to arrange the produce with respect to the cold wall in such a manner that no part of the produce is in actual contact with the cold wall which is apt to induce over-chilling of the produce.

More particularly it is proposed to provide one or more open-mesh baskets or produce containers for use in combination with a cold-wall refrigerator, the containers being arranged so as to be spaced from the walls and the bottom of the refrigerator. This allows cold air to descend along the cold wall and to enter the produce through the open-mesh sides and the bottom of the container, the cold air tending to absorb heat units from the produce and at the same time serving to entrain moisture from the outside space for deposit upon the produce.

It is further proposed to encourage flow or movement of the air in the manner described by making the upper rim portion of the produce container solid to provide a throat or flue between the container and the cold wall.

In the operation of the invention it has been observed that the degree of air-flow and the resulting cooling and moistening effects depend, to some extent, upon the spacing between the bottom of the refrigerator and the bottom of the produce container. In utilizing this phenomenon it is proposed to provide the containers with means for lowering and raising the same whereby it is made possible, for instance, to provide for different cooling and moistening effects for different produce containers within the same refrigerator.

2

It is further proposed to provide refrigerating means of the character described in which a plurality of produce containers, preferably of the same size and construction, may be accommodated in the same refrigerator and may be lifted out and inserted as individual units for re-filling operations or replacement by other units.

And finally, it is proposed to provide a cold wall refrigerator case adapted for receiving the produce containers, the case being made as an independent unit, equipped with cooling coils and insulation, and adapted for installation in any suitable cabinet or fixture, the case being equipped with a suitable refrigerating apparatus, whereby the overall cost of the installation is materially reduced and many existing installation problems may be met with greater facility.

Further objects and advantages of my invention will appear as the specification proceeds, and the novel features of my invention will be fully defined in the claims attached hereto.

The preferred form of my invention is illustrated in the accompanying drawing, in which:

Figure 1 shows a perspective view of a refrigerator made in accordance with my invention;

Figure 2, a sectional isometric view of a slightly different form of my refrigerator; and

Figure 3, a transverse section taken substantially along line 3—3 of Figure 2.

While I have shown only the preferred form of my invention, I wish to have it understood that various changes and modifications may be made within the scope of the claims attached hereto, without departing from the spirit of the invention.

Referring to the drawing in detail, my refrigerator 1 is of the open-top display type and is principally intended for the display of various kinds of produce, principally vegetables, in grocery stores, markets and the like, the principal object of the invention being to keep the produce in perfect condition during display by extracting heat units therefrom and by adding moisture in appropriate amounts.

The refrigerator case 2 may be made of any suitable form and is here shown as rectangular in shape, elongated and comprising a bottom 3, a front wall 4, a rear wall 5, and two end walls 6, the bottom and the walls being heavily insulated, as at 7, between metallic covers 8. A refrigeration coil 9 is suitably guided along the inner metallic cover to produce what is commonly known as a cold wall refrigerator. The top of the refrigerator is open for display of produce contained therein.

The case is intended to form a portable unit adapted for delivery to the store or market as an individual unit for installation in any suitable manner to suit the requirements and facilities of the store. It may be merely supported on legs, with refrigerating apparatus disposed in operative proximity, or may be inserted in a suitable cabinet or fixture already equipped with refrigerating apparatus, the coil 9 having two projecting ends 10 adapted for connection to the piping of the refrigerating apparatus, which latter may be of any suitable type and includes a compressor unit and any desired control devices not shown.

The coil 9 which is here shown only diagrammatically, is preferably arranged to provide a somewhat greater cooling effect along the top of the case than in the lower and bottom portion, which may be readily accomplished by suitable coil construction.

The rear wall of the case may be provided with a suitable superstructure 11, as shown in Figure 1, to provide shelves 12 for accommodating produce requiring less cooling and conditioning.

In combination with this case I provide a series of produce containers or baskets 13, preferably rectangular in form and of a depth corresponding substantially to the depth of the case.

These containers are dimensioned so that a selected multiple of the same, four in the case illustrated, substantially fill the case, leaving relatively narrow spaces 14 of uniform width between the containers, and similar spaces 15 between the end containers and the end walls of the case. From front to rear the containers are dimensioned to leave similar spaces 16 between the containers and the front and rear walls of the case. To insure proper and substantially uniform spacing all around each container, the latter may be provided with suitable spacing members 17 on the front and rear walls thereof.

The produce containers are supported on legs 18 which space the containers from the bottom wall of the case, and these legs are preferably made extensible, by means of screws 19 or the like, whereby the spacing may be adjusted.

In this manner the containers are spaced from each other and from the walls and the bottom of the case to provide air passages or flues to set up the air movement or air flow forming the principal object of the present invention.

The bottom and the sides of the containers are made of open mesh material, such as strands of wire indicated at 20, except for the upper rim portions 21 thereof, which are made of solid material such as sheet metal to form a throat between the upper end of each container and the case wall which serves to aid in the setting up of the desired air currents.

It should be understood, of course, that in use the containers are filled with produce, such as asparagus, string beans or the like, which cooperate with the containers in forming a substantially solid but porous body or mass allowing air to slowly trickle therethrough and furnishing the heat units to be extracted.

In the operation of the apparatus I find from actual experience that excellent cooling and moistening effects are produced. With the apparatus in operation, and the containers filled with string beans, for instance, the beans will not only reach, within a short time, a desired degree of coolness, but will also acquire a dewy coating of moisture which keeps the beans in a fresh and unwilted condition for an extended time period.

In a typical installation I employ a cold wall

temperature of approximately 28-31 degrees Fahrenheit and obtain a produce temperature of 36-45 degrees. The cooling effect depends somewhat upon the elevation of the container above the bottom of the case, the temperature rising as the container is raised and dropping as the container is lowered. But the container should not be lowered much beyond a point one inch above the floor of the case. It is possible, in this manner, to obtain different cooling effects for different containers in the same case.

The spacing between the containers and the side and end walls of the case may be about one inch and the solid or sheet metal portion of the container may extend downward about one-third of the way.

In operation a downward draft of cold air is set up in the passages or flues formed between the walls of the case and the containers and the cold air moves into the bottom passage and slowly circulates through the produce in the container, absorbing heat units and either dissipating into the atmosphere or returning to the side and end walls in a more or less well defined circulatory path. The circulation is very slow, preferably about 10 feet per minute.

As the air moves downward in the flues it also entrains moisture from the outside air, condenses the moisture and deposits the same on the outer surfaces of the individual parts of the produce. This keeps the produce in fresh condition, guards against wilting, and if the customer helps himself to a mess of string beans from one of the produce containers he will find the beans in the same fresh and cool condition as if he had picked them directly from the vine on a dewy morning.

It is apparent that in a modified form the solid rim portions 21 might be made as permanent parts of the case, with the open mesh containers suspended therefrom, without departing from the spirit of the invention.

I claim:

1. In refrigerating apparatus, an open-top refrigerator case having cooling means mounted within the walls thereof, and an open-mesh produce container disposed within the case, the container having side walls spaced from the side walls of the case so as to form unobstructed passages therewith adapted to set up circulation of chilled air through the container, and the upper edge portion of the container being made solid to encourage such circulation.

2. In refrigerating apparatus, an open-top refrigerator case having cooling means mounted within the walls thereof, and an open-mesh produce container disposed within the case, the container having side walls spaced from the side walls of the case so as to form unobstructed passages therewith and having a bottom spaced from the bottom of the case, whereby circulation of chilled air is set up through the passages and the bottom space into the container, and the upper edge portion of the container being made solid to encourage such circulation.

3. In a refrigerating apparatus, an open-top refrigerator case having cooling means within the wall means thereof, and an open-mesh produce container disposed within the case, the container having a side wall spaced slightly from a case side wall means so as to form a narrow vertical flue therewith, the flue being only approximately one inch wide to substantially prevent the building up of a counter-current when the air in the flue is cooled by the side wall means of the case and being adapted to set up a down-

ward draft of chilled air throughout the width thereof, and the flue being substantially unobstructed and having an upper end open throughout the width thereof and substantially on a level with the case wall means to cause outside air to spill over the edge of the case wall means for entraining in the downward draft.

4. In a refrigerating apparatus, an open-top refrigerator case having cooling means within the wall means thereof, and an open-mesh produce container disposed within the case, the container having a side wall spaced slightly from a case side wall means so as to form a narrow vertical flue therewith, the flue being only approximately one inch wide to substantially prevent the building up of a counter-current when the air in the flue is cooled by the side wall means of the case and being adapted to set up a downward draft of chilled air throughout the width thereof, and the flue being substantially unobstructed and having an upper end open throughout the width thereof and substantially on a level with the case wall means to cause outside air to spill over the edge of the case wall for entraining in the downward draft, and the container having a bottom similarly spaced from the bottom of the case to form a horizontal flue communicating with the vertical flue through the entire width thereof to guide part of the downward draft underneath the container.

5. In a refrigerating apparatus, an open-top refrigerator case having cooling means within the wall means thereof, and an open-mesh produce container disposed within the case, the container having a side wall spaced slightly from a case side wall means so as to form a narrow vertical flue therewith, the flue being only approximately one inch wide to substantially prevent the building up of a counter-current when the air in the flue is cooled by the side wall means of the case and being adapted to set up a downward draft of chilled air throughout the width thereof, and the flue being substantially unobstructed and having an upper end open throughout the width thereof and substantially on a level with the case wall means to cause outside air to spill over the edge of the case wall for entraining in the downward draft, and the container having a bottom similarly spaced from the bottom of the case to form a horizontal flue communicating with the vertical flue through the entire width thereof to guide part of the downward draft underneath the container, and the container having adjustable legs supporting the same whereby the width of the horizontal flue may be closely adjusted with respect to that of the vertical flue for producing different cooling effects.

6. In a refrigerating apparatus, an elongated, rectangular, open-top refrigerator case having a horizontal top edge and having cooling means within the walls thereof, a series of open mesh produce containers disposed within the case, and means for narrowly spacing the containers from the bottom of the case, the containers being of

rectangular shape and of a height to have their upper edges disposed in the top plane of the case, and the containers being dimensioned and positioned in the case to leave narrow vertical flues of substantially uniform width around each container, the width of the flues corresponding substantially to the spacing between the containers and the bottom of the case.

7. In a refrigerating apparatus, an elongated, rectangular, open-top refrigerator case having a horizontal top edge and having cooling means within the walls thereof, a series of open mesh produce containers disposed within the case, and means for narrowly spacing the containers from the bottom of the case, the containers being of rectangular shape and of a height to have their upper edges disposed in the top plane of the case, and the containers being dimensioned and positioned in the case to leave narrow vertical flues of substantially uniform width around each container, the containers having solid upper edge sections to accentuate the flue effect.

8. In a refrigerating apparatus, an open-top refrigerator case having cooling means within the wall thereof, and an open-mesh produce container disposed within the case, the container having a side wall spaced slightly from a case side wall so as to form a narrow flue therewith, and the flue being adapted to set up downward draft of chilled air therein and being located and arranged with respect to the case wall to cause outside air to spill over the edge of the case wall for entraining in the downward draft, said container also having a solid upper edge section adjacent the case wall to accentuate the flue effect.

9. In a refrigerating apparatus, an open-top refrigerator case having cooling means within the wall thereof, and an open-mesh produce container disposed within the case, the container having a side wall spaced slightly from a case side wall so as to form a narrow flue therewith, and the flue being adapted to set up downward draft of chilled air therein and extending upwardly to the level of the upper edge of the case wall so as to cause outside air to spill over the case wall edge for entraining the downward draft, said container also having a solid upper edge section adjacent the case wall to accentuate the flue effect.
